2608 11th Ave. NW., Calgary, Alberta, Canada

Filed May 14, 1965, Ser. No. 85,280

Term of patent 3½ years

(Cl. D48—20)

Fig. 2

The undisclosed rear is unornamented and plane except as indicated in the lower portion of FIG. 2.

The dominant features of our design reside in the portions shown in full lines.

This application is a continuation-in-part of D. 79,777, filed May 4, 1964 and now abandoned.

We claim:

The ornamental design for a purse light, as shown and described.
